UNITED STATES PATENT OFFICE

2,500,524

PUMP FOR CENTRALIZED LUBRICATING SYSTEMS

Ernest W. Davis, River Forest, Ill.

Application August 30, 1946, Serial No. 693,836

6 Claims. (Cl. 184—7)

1

My invention relates generally to pumps for centralized lubricating systems, and more particularly to control means for automatically relieving the pressure at the outlet of such pump at predetermined intervals.

In many centralized lubricating systems employing measuring valves, it is necessary for the proper operation of such measuring valves that the pressure in the supply line be relieved periodically to permit the valve mechanisms to be reset for a subsequent operation.

It is the object of my invention to provide a simple and effective pumping apparatus, which operates automatically to relieve the pressure in the supply line at predetermined time intervals.

A further object is to provide an improved electromagnetic means for maintaining a pressure relieving valve, connected to a centralized lubricating system, in open position for a predetermined time interval, provided a predetermined pressure in the lubricating system has been exceeded during a preceding time interval.

A further object is to provide an improved timing mechanism for centralized lubricating systems.

Other objects will be apparent from the following description, reference being had to the accompanying drawings, in which:

Fig. 1 is a central vertical sectional view of a preferred embodiment of my invention; and

Fig. 2 is a diagrammatic representation thereof, including a schematic wiring diagram.

Referring to Fig. 1, the lubricant pump is enclosed in a reservoir 10 for oil or the like, the pumping mechanism being supported on a shelf 12 which may be secured to the side walls of the reservoir 10 in any suitable manner, as by welding. The top 14 of the container is provided with a filling opening normally closed by a plug 16.

Suitably secured upon the shelf 12 is a small fractional horsepower pump driving motor 18 which, through a suitable speed reducing gearing contained within a housing 20, drives a crank disc 22 to which the upper end of a connecting rod 24 is pivotally connected. The lower end of the connecting rod 24 is secured to a piston rod 26 having a piston 28 reciprocable in a cylinder 30 formed in a cylinder block 32. The cylinder block is carried by a pipe 34 suitably secured at its upper end to the shelf 12. The lower end of the cylinder block 32 is notched to provide inlet ports 36. A screen 38 carried by a disc 40 attached to the block 32 prevents the admission of foreign particles to the pump.

2

The outlet port 42 of the pump is connected by a check valve 43 and conduit 44 with a pressure responsive device 46 which comprises a cylinder 48 in which a plunger 50 is reciprocable. Secured to the plunger 50 is a weight 52 made, at least in part, of soft iron or similar magnetic material.

The cylinder 48 has an outlet vent port 54. The interior of the cylinder 48 is in communication with the conduit 44 as well as a conduit 56 which leads to a branched conduit system 58, the latter leading to suitable measuring devices 60 which may be of any suitable construction, such, for example, as those shown in the patent to Teal No. 2,205,320 and the application of Frederick G. Schweisthal, Serial No. 570,961, filed January 1, 1945.

A timing motor 62, preferably a synchronous motor, operates through a suitable speed reducing gearing to drive a cam 64, the cam having a single high point adapted to actuate the resiliently biased operating arm 66 of a microswitch 68. The microswitch controls the energization of the motor 18, as well as an electromagnet 70 having a shading coil 71, which is secured to a mounting plate 72, the latter being suitably mounted on the shelf 12, and also serving as a mounting for the switch 68 and motor 62.

Referring now to Fig. 2, it will be noted that upon closure of a main switch 74, current is supplied to the timing motor 62, and after the cam 64 thereof has rotated through a small angle from the position shown, the microswitch arm 66 permits switch 68 to close, thereby supplying current to the motor 18 and electromagnet 70. When the motor 18 is energized, the piston 28 of the pump is reciprocated, this piston descending below the upper edges of the inlet ports 36 to admit lubricant, and discharging oil past the outlet port 42 and check valve 43. The pressure is thereby built up in the conduit system 56, 58, and supplied to the measuring valves or feeder devices 60. These devices are thus operated to supply measured charges of lubricant to the respective bearings to which they are connected.

After all of the devices 60 have operated, the continued operation of the pump builds up the pressure in the conduit system and in the lower end of the cylinder 48. When the pressure in the conduit system and cylinder 48 is sufficient to overcome the force of gravity acting upon the weight 52, the latter is elevated to a position approximately as shown in dotted lines in Fig. 2, in relatively close proximity to the poles of the electromagnet 70.

The shading coil 71 is used to prevent chatter-

ing whenever the apparatus is operated from alternating current. When the weight 52 is thus raised to the dotted line position of Fig. 2, the electromagnet 70 exerts a sufficient pull on the weight to draw it upwardly against the poles of the electromagnet, in which position the plunger 50 fully uncovers the vent port 54, and the oil under pressure in the conduit system 56, 58, as well as that supplied by the pump, is freely discharged through the vent port 54, thus reducing the pressure in the conduit system 58 substantially to atmospheric pressure. Under these conditions, the measuring devices 60 are free to reset themselves to normal condition in which they are ready to operate upon again supplying them with lubricant under pressure sufficient to operate them.

After a predetermined time interval, the cam 64 opens switch 68, thus deenergizing both the electromagnet 70 and a motor 18. As soon as the electromagnet 70 is deenergized, the weight 52 will force the plunger 50 to the position in which it is shown in full lines in Fig. 2, whereupon the system is in condition for repetition of the cycle above described.

While I have shown and described a preferred embodiment of my invention, it will be apparent that numerous variations and modifications thereof may be made without departing from the underlying principles of the invention. I therefore desire, by the following claims, to include within the scope of the invention all such variations and modifications by which substantially the results of my invention may be obtained through the use of substantially the same or equivalent means.

I claim:

1. In a lubricant supply system for centralized lubricating systems, the combination of a pump, an electric motor to drive said pump, a plurality of measuring devices operable to discharge measured quantities of lubricant to their associated bearings upon alternately supplying lubricant under pressure and relieving the pressure, a conduit system connecting the discharge of said pump to the measuring devices, a vertical cylinder having one end thereof in communication with the conduit system, said cylinder having a vent port spaced from said end, a plunger reciprocable in said cylinder and when in its lower position obstructing said vent port, a weight having a portion of magnetic material secured to the plunger and adapted to be elevated thereby when the lubricant pressure in the lower end of the cylinder exceeds that which can be resisted by the force of gravity acting upon the weight and plunger, an electromagnet located above the weight and of insufficient strength when energized to draw the weight from its lower position, but operable when the weight is raised a distance substantially sufficient to uncover the vent port to draw the weight to the electromagnet, and a time switch operated at predetermined intervals to energize said electric motor and said electromagnet.

2. In a lubricant supply system for centralized lubricating systems, the combination of a pump, means to drive said pump, a plurality of measuring devices each operable upon alternately supplying lubricant under pressure and relieving the pressure to discharge measured quantities of lubricant to their associated bearings, a conduit system connecting the discharge of said pump to the measuring devices, a cylinder having one end thereof in communication with the con-

duit system, said cylinder having a vent port spaced from said end thereof, a plunger reciprocable in said cylinder, a weight having a portion of magnetic material operatively connected to the plunger and adapted to be elevated thereby when the lubricant pressure in the conduit system exceeds that which can be resisted by the force of gravity acting upon the weight, an electromagnet located above the weight and of insufficient strength when energized to draw the weight from its lower position, but operable to draw the weight to the electromagnet when the weight is raised a distance substantially sufficient to uncover the vent port, and a time switch operated at predetermined intervals to energize said electromagnet.

3. In a lubricant supply system for centralized lubricating systems, the combination of a pump, means to drive said pump, a conduit system connected to receive the discharge of the pump, a vertical cylinder having one end thereof in communication with the conduit system, said cylinder having a vent port spaced from said end thereof, a plunger reciprocable in said cylinder, a weight having a portion of magnetic material secured to the plunger and adapted to be elevated thereby when the lubricant pressure in the lower end of the cylinder exceeds that which can be resisted by the force of gravity acting upon the weight and plunger, an electromagnet located above the weight and of insufficient strength when energized to draw the weight from its lower position, but operable when the weight is raised a distance substantially sufficient to uncover the vent port to draw the weight to the electromagnet, and a time switch operated at predetermined intervals to energize said electromagnet.

4. In a lubricant supply system for centralized lubricating systems, the combination of a pump, means to drive said pump, a conduit system connected to receive the discharge of said pump, a cylinder having one end thereof in communication with the conduit system, said cylinder having a vent port spaced from said end thereof, a plunger reciprocable in said cylinder, a weight having a portion of magnetic material operatively connected to the plunger and adapted to be elevated thereby when the lubricant pressure in the lower end of the cylinder exceeds that which can be resisted by the force of gravity acting upon the weight, an electromagnet located above the weight and of insufficient strength when energized to draw the weight from its lower position, but operable to draw the weight to the electromagnet when the weight is raised a distance substantially sufficient to uncover the vent port, and a time switch operated at predetermined intervals to energize said electromagnet.

5. In a lubricant supply system for centralized lubricating systems, the combination of a pump, means to drive said pump, a conduit system connected to receive the discharge of said pump, a cylinder having one end thereof in communication with the conduit system, said cylinder having a vent port spaced from said end thereof, a plunger reciprocable in said cylinder, a weight of magnetic material secured to the plunger to be elevated thereby when the force due to the lubricant pressure in the lower end of the cylinder exceeds that which can be resisted by the force of gravity acting upon the weight and plunger, means to hold the weight in raised position after it has been elevated a distance substantially sufficient to cause the plunger to uncover the vent

port, and periodically operating means to render said holding means ineffective.

6. In a lubricant supply system for centralized lubricating systems, the combination of a pump, means to drive said pump, a conduit system connected to receive the discharge of the pump, a vertical cylinder having one end thereof in communication with the conduit system, said cylinder having a vent port spaced from said end thereof, a plunger reciprocable in said cylinder, and when in its lower position obstructing the vent port, a weight having a portion of magnetic material secured to the plunger and adapted to be elevated thereby to uncover the vent port when the force due to lubricant pressure in the lower end of the cylinder exceeds that which can be resisted by the force of gravity acting upon the weight and plunger, an electromagnetic

means effective to hold the weight and plunger in a position in which the plunger uncovers the vent port, said electromagnetic means being effective only after the weight and plunger have been moved substantially to said last named position.
